ABSTRACT: A double-flow, two-pressure circuit interrupter of the downstream valve type is mounted inside of and insulated from a metal tank containing an interrupting medium at a relatively low pressure. The interrupter is enclosed in an insulating housing containing the medium at a high pressure. The continuous current path is through retractable contact bridging fingers which bridge a slidable movable arcing contact. During an interruption, downstream valves and the contact bridging fingers are opened first, then the slidable movable arcing contact is timed by a synchronous control device to open slightly before a current zero. The slidable movable arcing contact is driven by a mechanical energy storage mechanism.

DUAL-PRESSURE COMPRESSED GAS CIRCUIT BREAKER WITH A DOWNSTREAM BLAST VALVE COOPERATIVE WITH INTERRUPTER HOUSING IN DEFINING HIGH-PRESSURE REGION AND WITH SPACED BREAKER TERMINAL DISPOSED WITHIN SAID HIGH-PRESSURE REGION

This invention relates, generally, to circuit breakers and, more particularly, to circuit breakers of the synchronous type which have their arcing contacts opened just prior to a current zero of an alternating current wave.

Most of the synchronous circuit breakers described in prior patent applications have been of relatively low-power ratings and have not been suitable for relatively high voltage service. An object of this invention is to provide a synchronous breaker suitable for 69 kv., 5,000 mva. service.

Another object of the invention is to provide a circuit breaker which is relatively small in size, low in weight, and which has a relatively high interrupting rating.

A further object of the invention is to provide a double-flow, downstream valve, gas-blast circuit interrupter for a circuit breaker of the dual-pressure type.

Still another object of the invention is to provide a circuit interrupter having a low-moving mass and a short stroke, thereby making it suitable for synchronous operation.

A still further object of the invention is to provide contact means for bridging the synchronous arcing contact member of a circuit interrupter.

Another object of the invention is to provide for sequential operation of the synchronous arcing contact member and the bridging contact means.

A further object of the invention is to provide for opening the downstream valves and the bridging contact means simultaneously, but closing the valves independently of the bridging contact means.

Other objects of the invention will be explained fully hereinafter or will be apparent to those skilled in the art.

In accordance with one embodiment of the invention, a double-flow, two-pressure circuit interrupter of the downstream-valve type is mounted inside of and insulated from a metal tank which is at ground potential. The interrupter is enclosed in an insulating housing containing an interrupting medium, such as SF₆ gas, at a relatively high pressure. The outer tank contains the interrupting medium at a relatively low pressure. The continuous current path is through retractable contact fingers which bridge a slidably moving arcing contact. During an interruption, downstream valves and the contact bridging fingers are opened first, then the slidably moveable arcing contact is timed by a synchronous control device to open slightly before a current zero. The valves are reclosed shortly after interruption takes place. During a closing operation, the slidably arcing contact closes first after which the retractable fingers close. The slidably arcing contact is driven by a mechanical energy storage mechanism. The retractable bridging contact fingers are opened by the same device that operates the valves.

For a better understanding of the nature and objects of the invention, reference may be had to the following detailed description, taken in conjunction with the accompanying drawings, in which:

FIG. 1 is a view, partly in elevation and partly in section, of a circuit breaker embodying features of the invention;

FIG. 1A is a detail fragmentary view looking in the direction of arrow A in FIG. 1;

FIG. 2 is a diagrammatic view of the interrupter, its operating mechanism and control system utilized in the circuit breaker shown in FIG. 1, the interrupter being a partly open arcing position;

FIG. 3 is a graphical view showing the relation of the currents and the flux in the synchronous control device utilized in the control system shown in FIG. 2;

FIG. 4 is a detail view of an alternate method of supporting the interrupter inside the breaker tank, and,

Figs. 5 and 6 are views, similar to FIG. 2, showing the interrupter in the fully closed position and the fully contact-open arcing position, respectively.

A single pole-unit of a circuit breaker embodying the present invention is shown in FIG. 1 of the drawings. Additional pole-units, similar to the one shown, may be utilized to provide a multipole breaker. The structure shown in FIG. 1 comprises a generally cylindrical metal tank 11 supported by a metal framework 12, a circuit interrupter 13, an operating mechanism and compressor unit 14, porcelain weather casings 15 and 16, which insulate power conductors L1 and L2, respectively, from the tank 11, and current transformers 17, which may be mounted at either end of the tank 11.

The interrupter 13 is supported inside the tank 11, which is at ground potential, by means of insulating support rods 18 attached to the end of the tank 11 and to the interrupter housing 19 in the manner shown. A control unit and mechanical energy storing mechanism 21 is located at one end of the interrupter unit 13. The metal tank 11 has a closed bottom cylinder 11a welded to it. The joint between 11 and 11a is well rounded to reduce voltage stress gradient. An insulating operating rod 22 extends from the mechanism housing 14 to the control unit 21. The rod 22 may be in two sections joined through a rotatable shaft 20 which extends through the side of the cylinder 11a. The tank 11 and the cylinder 11a contain an interrupting medium, such as air, or preferably SF₆ gas, at a relatively low pressure. A portion of the interrupter unit 13 contains the interrupting medium at a relatively high pressure. Insulating feed pipes 23 and 24 connect the tank 11 and the interrupter unit 13, respectively, with the compressor in the mechanism and compressor unit 14. The gaseous interrupting medium is withdrawn from the bottom of the cylinder 11a through the pipe 23, filtered and compressed, and returned to the interrupter 13 through the pipe 24. As shown in FIG. 4, the interrupter unit 13 and the mechanism 21 may be supported by an insulating tube 18a which extends into the cylinder 11a and is attached to the cylinder by a U-shaped ring 18b.

The mechanical energy storage mechanism 21 may be generally of the type described in a copending U.S. Pat. application (Case No. 36,125) Ser. No. 369,208, filed May 21, 1964, now U.S. Pat. No. 3,284,732, issued Nov. 8, 1966 to 40 Fritz Kesselring. However, it differs from the prior mechanism in many respects. As shown more clearly in FIG. 2, the mechanism comprises a flywheel 25 driven by a ratchet pawl 26, a clutch wheel 27 connected to the flywheel 25 by a shaft 28, and the operating rod 22, which is actuated by a suitable actuator, such as a solenoid 30. An air piston and cylinder, or other suitable actuator, may be utilized in place of the solenoid 30. The upper end of the rod 22 is connected to one arm of a bellcrank lever 31 pivotally mounted on a support 32. The other arm of the lever 31 is connected by a link 33 to an arm 34, which carries the ratchet pawl 26. The arm 34 is rotatably mounted on the shaft 28. When the rod 22 is moved downwardly by the solenoid 30, the pawl 26 engages teeth 35 on the flywheel 25 to drive the wheel in a clockwise direction. The rod 22 is biased upwardly by a spring 36, which engages the one arm of the lever 31.

As also shown in FIG. 2, the housing 19 for the interrupter unit 13 is generally cylindrical in shape, and is composed of a suitable insulating material. Two generally round terminals 41 and 42 are disposed inside the housing 19 in spaced relation. The terminal 41 has an annular flange 43 thereon, and the terminal 42 has an annular flange 44 thereon, which engage the inner wall of the housing 19 to retain the interrupting medium in a space 45 between the terminals at a relatively high pressure. As explained hereinbefore, the interrupting medium is supplied to the region 45 between the terminals through the feed pipe 24. The terminal 41 has a generally Y-shaped opening 46 therethrough, and the terminal 42 has a generally Y-shaped opening 47 therethrough. As shown by the dashed lines 48a, a valve 48 closes the arms of the opening 46 to prevent the medium from flowing through the opening when the valve 48 is closed. Likewise, a valve 49 closes the arms of the Y-shaped opening 47, as shown in FIG. 5, to prevent the medium from flowing through this opening when the valve 49 is closed.

A hollow movable arcing contact 51 is slidably disposed in the leg of the Y-shaped opening 47 and, as shown by the dashed lines 51a in FIG. 2, extends into the leg of the Y-shaped opening 46 to engage spring-biased contact fingers 52 mounted in the terminal 41, thereby electrically connecting the terminals 41 and 42 when the arcing contact 51 is in the closed position, as shown in FIG. 5. The contact 51 is actuated by an operating rod 53 which is reciprocated by the stored-energy mechanism 21, as will be described more fully hereinafter. The rod 53 is engaged by contact fingers 54 provided on a portion 55 of the terminal 42. The valve 49 is slidably disposed on the terminal portion 55. Likewise, the valve 48 is slidably disposed on a portion 56 of the terminal 41. The valves 48 and 49 are operated in a manner described more fully hereinafter.

In order to reduce the size and the mass of the movable arcing contact 51, a main current path through the interrupter is provided through retractable contact bridging fingers 57, which are pivotally mounted in recesses 58 in the terminal 42. As shown in FIG. 5, the fingers 57 engage a projection 59 on the terminal 41 when they are closed, thereby bridging the movable arcing contact 51 when it is closed. Thus, the main current path is into terminal 41, through the bridging fingers 57, and out through terminal 42.

As shown, the terminals 41 and 42 are contoured in such a way as to give a nearly uniform electrical field across them in the open position. Furthermore, as explained hereinafter, the valves 48 and 49 are reclosed after an interruption, thereby maintaining the interrupting medium in the space between the terminals at a relatively high pressure when the breaker is open. Thus, the distance between the terminals 41, 42 may be relatively small.

As shown in FIG. 2, the linkage of the interrupter is in the partly open position of the circuit breaker showing the arcing condition. In the breaker-closed position, shown in FIG. 5, the movable contact 51 engages the contact fingers 52. The retractable contact fingers 57 engage the portion 59 of the terminal 41. The valves 48 and 49 are in the position shown by the full lines in FIG. 5, thereby sealing off the high-pressure interrupting medium in the region 45, from the low-pressure medium in tank 11. A spring-biased detent 61 is in a notch 62 in the shaft 53, thereby holding the movable contact 51 closed, as shown in FIG. 5. As previously explained, the bridging fingers 57 are the main current-carrying fingers.

When the current in the conductor L2 exceeds a predetermined amount because of a fault condition, a relay 63 is energized by a current transformer 64. Contact members 65 of the relay are closed to energize the solenoid 30 through normally-closed contact members 66 on the solenoid, as shown in FIG. 5. The operating rod 22 is then moved downwardly to drive the flywheel 25 and the clutch wheel 27 clockwise through the ratchet 26, as previously explained. At the same time the lever 31 drives a pair of links 67 to the right, which, in turn, drive links 68 to the right to operate bellcrank levers 69, thereby disengaging the contact bridging fingers 57 from the surface 59 to open the bridging circuit through these fingers, as shown in FIG. 2. The movable contact 51 now carries the full current as shown in FIG. 2. The links 68 also drive latches 71 to the right, thereby opening blast valves 49 and 48 to permit the interrupting medium to flow from the high-pressure region 45 to a low-pressure region through the Y-shaped openings in the terminals 41 and 42, as shown in FIG. 2. The valve 48 is connected to the valve 49 through an insulating rod 72, a lever 73 and links 74.

When a trip solenoid 75 is energized, it drives a dog 76 counterclockwise by means of a lever 76a to engage a V-groove 77 in the clutch flywheel 27. The head of the dog 76 is shaped to fit into the V-shaped groove 77 and frictionally engage the sides of the rotating groove. The dog 76 is carried by an arm 78 rotatably mounted on the shaft 28. The arcing contact 51 is now driven to the right or open position through a link 79 and a lever 81 pivoted at 82. This is timed by a synchronous control device 83 to occur 1 to 2 milliseconds be-

fore a current zero. When the contact 51 moves to the full open position, as shown in FIG. 6, a detent 61 moves into a notch 84, thereby holding the arcing contact 51 in the open position. The current is interrupted at current zero.

5 The latches 71 are disengaged from the blast valve 49 when the latches hit kickoff pins 85. This releases valves 48 and 49 allowing them to reclose under the action of a spring 86, thereby shutting off the flow of the interrupting medium. However, the reclosing of the valves 48 and 49 is delayed a predetermined time by a dash-pot 87, or other suitable time-delay device, to permit the current to be interrupted at a second or later current zero in case it is not interrupted at the first current zero, as will be explained more fully hereinafter.

15 Spring-biased latches 88 enter notches 89 in the links 68, thereby holding the contact bridging fingers 57 in the open position. The dog 76 is released from the clutch 27 by a kickoff probe 91. The operating rod 22 and associated linkage are reset by the spring 36. The rod 22 is shown in its reset position in FIG. 5 and in its actuated position in FIG. 6. The links 67 are free to reset, or move to the left independently of the links 68. Thus, the valves 48 and 49 are opened simultaneously with the bridging contact fingers 57, but the valves are reclosed independently of the bridging contact fingers.

25 Furthermore, the opening of the blast valves and the retractable contact bridging fingers is disassociated from the opening of the movable arcing contact 51. This means that the mechanism driving the moving arcing contact can be made smaller than would otherwise be possible.

30 The reclosing of the valves after an interruption conserves the high-pressure interrupting medium, and also permits the open-circuit voltage to be held across the terminals 41 and 42 through the high-pressure medium. The gas-flow paths through the terminals 41 and 42 are shaped to give a region of high-velocity approach upstream and radial to the arc, and allow for expansion of the heated gas downstream of the arc during an interruption.

35 To start a closing sequence of the circuit breaker, a push button 92 is closed, thereby energizing a solenoid 90 to close a circuit through contact members 93 and normally closed contacts of antipumping relay 100 to energize the solenoid 30, and drive the operating rod 22 downwardly to rotate the flywheel 25 and the clutch wheel 27 clockwise in the manner previously described. The circuit through the solenoid 30 is interrupted by the opening of contacts 66 after a delayed time, and the rod 22 and associated linkage reset under action of the spring 36. The relay 100 is energized simultaneously with the solenoid 30 and remains energized until the pushbutton is released, thereby preventing pumping of the solenoid 30. The rod 22 now goes into overtravel in an upward direction which occurs only on a closing operation. Overtravel upwardly during a tripping operation is prevented by a latch 94, which engages a projection 95 on the rod 22. The latch 94 is biased to the closed position by a spring 96, and is released by the solenoid 90 when it is actuated to close the contact members 93 to energize the solenoid 30, as previously described.

40 A projection 97 on the link 67 drives a pivoted lever 98 counterclockwise to engage a dog 99 with the groove 77 in the clutch wheel 27. The dog 99 is carried by an arm 101 rotatably mounted on the shaft 28. The movable arcing contact 51 is driven to the left, or closed position by a link 102 and a lever 103 pivoted at 104. Near the end of the stroke of the contact 51 a projection 105 engages the latches 88 to release the latches, thereby permitting the bridging contact fingers 57 to reclose, and the latches 71 to reset under the action of springs 106, which engage the levers 69. The links 67 are free to move to the left independently of the links 68, which actuate the bridging contact fingers 57, but engage the links 68 when they are moved to the right. A kickoff probe 107 releases the dog 99 from the clutch wheel 27. As previously explained, the detent 61 enters the notch 62 to retain the arcing contact 51 in the closed position until it is opened in the manner hereinbefore described.

If the breaker should fail to interrupt at the first current zero, the arcing contact 51 can be immediately reclosed by energizing a solenoid 108 to actuate the lever 98 to engage the dog 99 with the clutch wheel 27. The arcing contact 51 is then reopened just prior to a second current zero by energizing the solenoid 75. The energization of the solenoids 108 and 75 is controlled by the synchronous control device 83.

One form of synchronous control device, which may be utilized is described in a copending U.S. Pat. application Ser. No. 419,045, filed Dec. 17, 1964, now U.S. Pat. No. 3,379,850, issued to F. A. Azinger, and assigned to the Westinghouse Electric Corporation. As described in the Azinger patent, the synchronous control device 83 comprises a saturating core 111 having a main airgap 112 and at least one other airgap 113 therein. An armature coil 114 is disposed on an armature core 115 rotatably mounted in the airgap 112. A contact arm 116 is carried by the armature core 115. The conductor L2 is disposed on the core 111 to energize the core by the current to be interrupted.

The operation of the synchronous device may be understood by referring to FIG. 3. As shown, the current I_1 , which is the current to be interrupted, sets up a flux B in the magnetic core 111. At t_0 the magnetic circuit becomes saturated. At t_1 , the core 111 unsaturates when the current decreases below a predetermined amount, and the rapid rate of change in the flux B which takes place as the current I_1 approaches zero induces a secondary current i_2 in the armature coil 114, which reacts with the flux across the airgap 112 to produce a torque which rotates the armature coil 114. This torque is in one direction from t_1 to t_2 , but reverses as the current I_1 passes through zero at t_2 since the flux B is in the opposite direction while the current i_2 continues to flow in the same direction. The reversal of the torque reverses the direction of rotation of the armature coil 114. The current i_2 drops to zero at t_3 when the magnetic core is saturated during the other half-cycle of the current i_1 . At t_4 the core again unsaturates, and the current i_2 is in the opposite direction and reacts with the flux B to produce a torque to rotate the coil 114 and the arm 116 in the original direction. The torque reverses when the current I_1 passes through zero at t_5 . The current i_2 drops to zero at t_6 . Thus, the contact arm 116 is oscillated back and forth.

The oscillation of the contact arm 116 is restrained by tension springs 117 and 118 attached to the arm 116 at opposite sides of the armature core 115. Thus, the contact arm 116 is prevented from engaging stationary contacts 121 and 122 or contacts 123 and 124 so long as the current flowing in the conductor L2 is below a predetermined amount. However, when the current exceeds a predetermined amount, the arm, which will have been already in motion, can, because of the greater torque available, overcome the spring loading and travel to meet a set of stationary contacts, thereby causing the device 83 to function as a synchronous-current relay.

In the present system, the device 83 is utilized as a synchronous relay to initiate the opening of the movable contact member 51. As explained hereinbefore, this is done by energizing the solenoid 75. As shown, when the contact arm 116 bridges contacts 121 and 122, a conductor 125 is energized. The conductor 125 is connected to the solenoid 75 through auxiliary contact members 126, actuated by the operating rod 53, and a conductor 127. The auxiliary contacts 126 are closed when the main contact 51 is closed. The energization of the solenoid 75 effects the opening of the contact 51 in the manner hereinbefore described.

As explained hereinbefore, the device 83 is utilized to cause the contact 51 to be immediately reclosed if the current is not interrupted at the first current zero. As previously explained, the torque on the contact arm 116 reverses with each half-cycle of the alternating current wave. Thus, if the current is not interrupted at the first current zero, the contact arm 116 bridges contacts 123 and 124 to energize a conductor 128. The conductor 128 is connected to the solenoid 108 through auxiliary contacts 129 and a conductor 131. The contacts 129

are actuated by the operating rod 53, and are closed when the main contact 51 is in the open position. After the main contact 51 is reclosed, it is reopened just prior to the second current zero in the same manner as it was opened prior to the first current zero. The contact 51 continues to reclose and reopen until the current is interrupted.

The synchronous control device 83 controls the operation of the moving contact 51. Control devices of other types may be utilized, if desired. Also, operating mechanisms of other types may be utilized.

If desired, the circuit breaker may be opened nonsynchronously by closing a pushbutton 132 to energize a solenoid 130, thereby closing a circuit through contact members 133 to energize the solenoid 30 which drives the rod 22 downwardly to rotate the flywheel 25 and the clutch wheel 27 clockwise as previously described. Overtravel of the rod 22 downwardly is now permitted since a latch 134 is moved to the left where it will not engage a projection 135 on the rod 22. Normally, the latch 134 is biased by a spring 136 to prevent downward overtravel by engaging the projection 135. The downward overtravel of the rod 22 causes a probe 67a on the lower link 67 to engage the lever 76a which actuates the dog 76 into engagement with the rotating clutch wheel 27, thereby opening the breaker as previously described.

From the foregoing description it is apparent that the invention provides a circuit interrupter having a moving contact, which is relatively low in mass and travels a relatively short distance. Thus, the operating mechanism for the moving contact can be made small since the operation of the main current carrying contact bridging fingers and the valves is disassociated from the moving arcing contact. The double-flow, downstream valve arrangement makes efficient use of the interrupting medium. Maintaining the interrupting medium at a high pressure between the stationary terminals of the breaker, when the contacts are in the open position, permits the distance between the terminals and between the contacts to be relatively small, thereby reducing the size of the interrupter, and, consequently, the overall size of the circuit breaker. The breaker is of the dead tank construction. Conventional current transformers can be utilized with the breaker.

Since numerous changes may be made in the above described construction and different embodiments of the invention may be made without departing from the spirit and scope thereof, it is intended that all subject matter contained in the foregoing description, or shown in the accompanying drawing shall be interpreted as illustrative, and not in a limiting sense.

We claim:

1. In a gas-blast circuit breaker, in combination, a metal tank for containing an interrupting gaseous medium at a relatively low pressure, an interrupter housing mounted inside of and insulated from the tank, terminals spaced inside the interrupter housing, a movable arcing contact connecting said terminals, retractable contact means bridging the movable arcing contact when closed, valve means disposed within said interrupter housing and defining with the interrupter housing a high-pressure region, said terminals disposed within the high-pressure region, said valve means functioning as a downstream blast valve, actuating means for opening the bridging contact means and the valve means simultaneously, and additional actuating means for opening the movable arcing contact.

2. The combination defined in claim 1 including means for reclosing the valve means independently of the bridging contact means.

3. The combination defined in claim 1 wherein the additional actuating means opens the movable arcing contact after the opening of the movable bridging contact means and the valve means, and including control means for controlling the operation of the additional actuating means.

4. The combination defined in claim 1 wherein the additional actuating means opens the movable arcing contact after the opening of the bridging contact means and the valve means, and including synchronous control means for con-

trolling the operation of the additional actuating means to open the movable arcing contact a short time before a current zero of an alternating current wave.

5. The combination defined in claim 4 wherein the synchronous control means controls the operation of the additional actuating means to reclose the movable arcing contact if the current is not interrupted at the current zero.

6. The combination defined in claim 1 wherein the terminals have openings therein and the movable arcing contact is movable in said openings to electrically connect the terminals, and the valve means permits the interrupting medium to flow through the openings when opened.

7. The combination defined in claim 6 including means for reclosing the valve means independently of the bridging contact means.

8. The combination defined in claim 1 wherein the additional actuating means comprises mechanical energy storage means for opening the movable arcing contact after the opening of the contact bridging means and the valve means, and including control means for controlling the operation of the mechanical energy storage means.

9. The combination defined in claim 8 wherein the control means is a synchronous control means for controlling the operation of the mechanical energy storage means to open the movable arcing contact a short time before a current zero of an alternating current wave.

10. The combination defined in claim 9 wherein the synchronous control means controls the operation of the mechanical energy storage means to reclose and then reopen the movable arcing contact if the current is not interrupted at the first current zero.

11. A circuit interrupter comprising a generally cylindrical insulating housing, two terminals disposed inside the housing in spaced relation to retain an interrupting medium between the terminals at a relatively high pressure, each terminal having an opening therethrough, valve means preventing the medium from flowing through the openings, a movable arcing contact movable in said openings to connect the terminals, contact bridging means mounted on one terminal and engaging the other terminal to bridge the movable arcing contact, actuating means for opening the contact bridging means and the valve means, and additional actuating means for opening

the movable arcing contact.

12. The circuit interrupter defined in claim 11 wherein the movable arcing contact is a hollow contact member, the contact bridging means are pivotally mounted on one terminal and interrupt the bridging circuit when opened, the valve means permit the interrupting medium to flow through the opening and the hollow movable arcing contact member when opened, and the hollow movable arcing contact member interrupts the circuit through the interrupter when opened.

10 13. The circuit interrupter defined in claim 12 including control means for controlling the operation of the actuating means to cause the movable arcing contact member to open after the opening of the contact bridging means and to close before the closing of the contact bridging means.

15 14. The circuit interrupter defined in claim 11 wherein each terminal has an annular flange thereon engaging the wall of the housing, each terminal has a generally Y-shaped opening therethrough, the valve means close the arms of the openings to prevent the medium from flowing through the openings, the movable arcing contact is a hollow contact member slidably disposed in the leg of one opening and engaging the leg of the other opening to electrically connect the terminals, and the bridging contact means and the valve means are opened simultaneously to interrupt the electrical bridging circuit and to permit the interrupting medium to flow through the openings and the hollow arcing contact member.

15 15. The circuit interrupter defined in claim 14 including means for reclosing the valve means independently of the contact bridging means.

30 16. The combination defined in claim 8 wherein the control means is a nonsynchronous control means for controlling the operation of the mechanical energy storage means to open the movable arcing contact.

17. The combination defined in claim 16 wherein the nonsynchronous control means includes overtravel means.

35 18. The combination defined in claim 17 wherein the overtravel means is manually controlled.

19. The combination defined in claim 17 including electromechanical means for supplying energy to the mechanical energy storage means, and the overtravel means is associated with said electromechanical means.
